Des. 237,247
Patented Oct. 21, 1975

237,247

PICK UP TOOL

Raymond B. Nockleby, Rte. 1,
Kalispell, Mont. 59901

Filed Apr. 18, 1974, Ser. No. 461,988

Term of patent 14 years

Int. Cl. D8—05

U.S. Cl. D8—52

FIG. 1 is a perspective view of the pickup tool;
FIG. 2 is a side elevation view, the opposite side being
a mirror image;

FIG. 3 is a top view;

FIG. 4 is a bottom view;

FIG. 5 is an enlarged end view from the left in FIG.
2; and

FIG. 6 is an enlarged end view from the right in
FIG. 2.

I claim:

The ornamental design for a pick up tool, as shown
and described.
